UNITED STATES PATENT OFFICE

2,680,619

REMOTE CONTROL BOMBING GAME APPARATUS

Orva W. Reiter, Tiffin, Ohio

Application May 22, 1950, Serial No. 163,497

3 Claims. (Cl. 273—95)

1

The present invention relates to improvements in remote control bombing game apparatus.

An object of the present invention is to provide an aerial projectile apparatus which is electrically operated and is provided with a bomb rack having a plurality of bombs therein which is completely operated by remote control means whereby the aerial movement of the aircraft and the time of bomb release are controlled by a remotely situated operator.

A further object of the present invention is to provide a game apparatus which measures the skill of an operator in releasing bombs to strike predetermined targets.

Another object of the present invention is to provide a game bombing structure in which the bomb release apparatus is simple in construction and easily actuated.

A still further object of the present invention is to provide a novel supporting arrangement of the aircraft whereby the aircraft is freely rotatable about an upstanding member which is removably mounted upon a base target means.

A still further object of the present invention is to provide novel connecting arrangements between the base target means and upstanding member, and between the rotatable arm and the upstanding member, and between the aircraft and rotating arm.

The means by which the objects of the present invention are accomplished include a base target means, an upstanding bearing member removably mounted on the base target means, an arm pivotally mounted on the bearing member, a simulated aircraft mounted on the outer end of the arm, means for propelling the aircraft, the aircraft being provided with a bomb rack and plurality of simulated bombs, and means for releasing the bombs.

This invention also has for its objects to provide a game apparatus that is positive in operation, easily installed in operating arrangement and easily dismounted therefrom, economical of manufacture and relatively simple.

Various other objects and advantages will be apparent from the detailed description to follow. In the description as well as in the claims, parts and elements are identified by specific names for convenience, but such nomenclature is intended to be as generic in its application to analogous parts as the prior art will permit.

My invention is clearly illustrated in the accompanying drawings, wherein:

Figure 1 is a perspective view of the remote control bombing apparatus showing one form of target base;

2

Figure 2 is a vertical transverse sectional view taken substantially along the plane of 2—2 of Figure 1;

Figure 3 is a detailed sectional view of a part of the aircraft showing the bomb rack and bomb releasing means;

Figure 4 is a vertical transverse sectional view taken substantially along the plane of line 4—4 of Figure 3;

10 Figure 5 is a horizontal transverse sectional view taken substantially along the plane of line 5—5 of Figure 2;

Figure 6 is a detailed elevational view showing the connection between the rotating arm and the contact element of the upstanding member;

Figure 7 is a horizontal transverse sectional view taken substantially along the plane of line 7—7 in Figure 2;

Figure 8 is a top plan view of a modified form of the invention;

Figure 9 is a perspective view of one form of simulated bomb employed with the present apparatus;

Figure 10 is another form of simulated bomb used with the present invention; and

Figure 11 is a view showing the electrical circuit employed in the present invention.

Referring more particularly to the drawings, wherein like numerals designate like parts throughout, numeral 10 designates generally the game apparatus of the present invention which includes a base target means 12, an upstanding member 14 removably mounted on the base target means 12, an arm 16 removably and pivotally mounted on the upstanding member 14, a simulated aircraft 18 removably mounted on the arm 16 for rotation therewith. The control means for operating the electrical circuit in the present invention are included in the control board 20 which derives its power from a transformer 22 which is connected to a source of electrical power by means of a cable 24.

In the form of the invention illustrated in Figure 1, the target base means 12 is formed from a flat target member 26 having target indicia means 27 thereon, and side wall members 28, 30, 32 and 34. At one corner of the base target means 12, a four way control plug 36 is mounted in which a connector element 38 is adapted to be inserted, providing a connection between the control board 20 and the game apparatus.

As will be seen upon an examination of Figure 2, cable connecting means 40 and 42 are positioned beneath the base target board 26 and have their ends secured to the four terminals 44, 46, 48 and 50 and the plug element 52 secured on

the base board 26, as seen best in Figure 5. An annular member 54 is positioned around the plug element 52 and provides a base supporting ring for the upstanding member 14.

The upstanding member 14 is provided with a flanged base portion 56 which cooperatively engages the annular member 54 and is secured to the base target means by means of screws 58 and nuts 60 and 62. The upstanding member 14 is provided with a cable bore 64 in which a multilead cable 68 is positioned having its bottom end connected to plug element 70 which is complementary to the plug element 52 and adapted to be in engagement therewith when the upstanding member 14 is in position. The plug elements 52 and 70 are of the type that can be engaged in only one position.

The upstanding member 14 is provided with a reduced portion 72 at its upper end and a shaft recess 74 in axial alignment with the upstanding member 14. The reduced portion 72 is provided with a longitudinal slot 73 which communicates with the cable bore 64 and is adapted to receive the ends of the wire element of the cable 68. A plurality of contact elements 78 are mounted on insulating material 76 about the reduced portion 72 of the upstanding member 14. The wire ends 80 are each connected to one of the contact rings 78.

The shaft 82 is mounted in the shaft recess 74 and has a pair of bearing mountings 84 secured in spaced relation intermediate its ends. Between the bearing mountings 84 are provided a pair of conventional ball bearing units.

The arm 16 is provided with an enlarged sleeve portion 88 having a central bore 90 and a pair of sleeve inserts 92 and 94 secured in the bore 90 by means of screws 96. The sleeve inserts 92 and 94 are provided with bearing surfaces 98 for cooperation with the ball bearing unit 86 whereby the arm 16 is freely rotatable about the shaft 82 and is supported thereby.

The arm 16 is provided with a cable bore 100 having a cable 102 mounted therein, one end of the cable 102 having the ends of its individual wire elements connected to the plug connector 104 mounted on the bottom face of the arm 16. The other ends of the individual wire elements of the cable 102 are connected to the plug element 106 mounted on the upper face of the arm 16 by means of the screws 108.

As seen best in Figures 2 and 6, the commutator member 110 is formed from a rectangular mounting member 112 having a plug connector 114 mounted at its upper end for connection to the plug unit 106 by which the commutator member is mounted. A plurality of commutator fingers 116 are secured by pins 118 to one face of the commutator element 112 and are each connected to an individual wire element of the plug 114. Each of the commutator fingers 116 is adapted to resiliently engage one of the contact rings 78 providing an electrical connection between the elements of the cable 68 and the elements of the cable 102.

The simulated aircraft 18 is formed from sheet metal into any desired form and is provided at its forward end with an electrical motor 120 having a pair of wire connections to the plug 122 which is adapted to be connected to the plug 106. As seen in Figure 2, the plug 122 is secured to the simulated aircraft by means of the angle member 124 and the nuts and screws 126 and 128. The simulated aircraft 18 is provided with a bomb rack designated generally at 130 intermediate the

ends of the body portion. As seen best in Figure 3, the bomb rack 130 is formed from a pair of channel members 132 mounted in spaced relation to each other by means of brackets 134 which are connected to the interior of the shell of the simulated aircraft 18. A guard member 136 is secured to the channel members 132 and the sides of the aircraft by means of bracket 140 and screws 138. The aircraft shell is provided with a pair of openings 142 and 144 into which the bombs may be inserted for positioning in the bomb rack 130 and out of which the bombs may be expelled when released.

The bomb release means include a solenoid 146 secured to the back side of the bomb rack 130 and has a pair of wire connectors 148 for connection to the plug element 122. A plunger member 150 is resiliently mounted on the bomb rack 130 by means of spring element 152 and nuts and bolts 154 and 156. The plunger 150 is provided with a plate 158 having a threaded portion 160 inserted through the plunger 150 and secured thereon by means of nut 162, the plate 158 being in juxtaposition to the solenoid 146 whereby when said solenoid is actuated the plunger 150 is resiliently attracted to the solenoid 146. The end of the plunger 150 is formed into U-shaped portion 164 whereby the end 166 is received within the bomb rack and adapted to be positioned behind one of the bombs 170.

In the form of the invention shown in Figure 8, the target base means 172 is provided with a plurality of partition elements 174 dividing the space into a plurality of targets which may have pre-selected score indicia thereon whereby score may be kept in playing a game. In this form, the bombs when released from the rack will be retained between a pair of the partition elements 174. The simulated bomb 170 having control fins 171 as shown in Figure 9 would preferably be used with this form of base target means.

Figure 10 shows a modified simulated bomb structure 175 having a weighted and pointed end 176 and control fins 177 which is particularly adapted to be used in conjunction with the base target means 26 whereby when the bomb is released it will project against the target as a dart.

From the foregoing description of the structure of the present invention, it is believed that the method of assembly and operation of the present invention will be readily understood by one skilled in the art. In setting up the present invention, the transformer 22 and the control board 20 are connected by cable means as shown in Figure 1, and the plug 38 is connected to the socket 36. The upstanding member 14 is then secured in position so that the plug elements 52 and 70 cooperatively engage each other providing electrical connection and nuts 60 are tight to hold the upstanding member 14 in position. The arm 16 is then positioned on the shaft 82 with the supporting bearing element 86 in desired relation to the bearing surfaces 98 by means of the bearing mounting members 84. The simulated aircraft 18 is then mounted on the arm 16 by means of plug connection 122 to 106. The commutator member 110 is then plugged into the element 104 with the commutator fingers 116 engaging the commutator rings 78 on the upstanding member 14.

With the switch "on" at the control board 20 the rheostat 22 is slowly moved actuating the electrical motor in the simulated aircraft causing the propeller 19 to rotate, the aircraft 18 then 75 rotating about the upstanding member 14. The

rheostat 22 may then be adjusted to give the aircraft the desired speed of rotation. The operation of the electrical circuit may be readily understood from an inspection of Figure 11. The potential will be adjusted by the transformer in conjunction with the rheostat 22 to secure the desired operating potential for the device. Closing switch 21 on control panel 20 will apply potential to the motor circuit including the motor 120 and the speed control rheostat 29. Also closing the switch 21 will apply potential to the circuit 148 containing switch 23 and the bomb release solenoid 146. The solenoid 146 will be controlled by switch 23 to actuate the bomb rack to release the bombs therein. The speed of the motor 120 will be regulated by rheostat 29 which is adjustable by control knob A on control panel 20. The propeller 19 driven by motor 120 will cause rotation of the simulated aircraft about the upstanding member 14.

From the foregoing, it is believed that an apparatus has been provided which will accomplish all of the objects hereinabove set forth and which will provide a means of entertainment which can be used not only in the home but at fairs, carnivals and the like.

Some changes may be made in the construction and arrangement of the parts of my device without departing from the real spirit and purpose of my invention.

Having described the invention, what is claimed as new is:

1. A remote control bombing apparatus comprising a base target means, an upstanding bearing member mounted on said base, an arm pivotally mounted on said bearing member, a simulated aircraft mounted on said arm, means for propelling said aircraft, a bomb rack in said simulated aircraft, a bottom stop in said rack, said rack having a lateral slot therein, a plurality of simulated bombs in said rack, a plunger resiliently mounted on said bomb rack, one end of said plunger being positioned on said rack and contacting the bomb in proximity with said slot, a solenoid mounted in juxtaposition to an intermediate portion of said plunger, an electrical circuit connected to said solenoid, control means in said circuit for energizing said solenoid, said solenoid actuating said plunger to force a bomb laterally through said slot.

2. In a remote control bombing apparatus having a base target means and a simulated aircraft

movable over said base, a bomb release comprising a bomb rack mounted in said simulated aircraft, said aircraft having an upper aperture in alignment with said bomb rack for filling simulated bombs into said rack and a discharge aperture below and to the rear of said rack, said rack having a lateral bomb slot adjacent the bottom thereof, a plunger aligned with said bomb slot, a solenoid operatively associated with said plunger, an electrical circuit including a control device connected to said solenoid, said solenoid when energized urging said plunger transversely of said bomb rack to displace a bomb laterally from said rack through said slot.

- 10 3. In a remote control bombing apparatus having a base target means and a simulated aircraft movable over said base, a bomb release comprising a bomb rack mounted in said simulated aircraft, said aircraft having an upper aperture in alignment with said bomb rack for filling simulated bombs into said rack and a discharge aperture below and to the rear of said rack, said rack having a lateral bomb slot adjacent the bottom thereof, a plunger aligned with said bomb slot, a solenoid operatively associated with said plunger, an electrical circuit including a control device connected to said solenoid, said solenoid when energized urging said plunger transversely of said bomb rack to displace a bomb laterally from said rack through said slot, a guard member secured to the rack extending through said discharge aperture.
